ABSTRACT

A carburetor for internal combustion engines of the type including the idling system, provides guide passage means for conducting the flow of fuel, which tends to adhere in the state of liquid upon the inner wall surface of the throttle bore in idling or low-load operations of the associated engine, down onto the bottom area of the throttle valve, so that the whole of liquid fuel be thoroughly atomized before leaving the carburetor.

CARBURETOR FOR INTERNAL COMBUSTION ENGINES

BACKGROUND OF THE INVENTION

The present invention relates to a carburetor for internal combustion engines, and more particularly to an improved carburetor which has excellent characteristics of carburetion in terms of complete atomization of the fuel attainable in starting, idling or low-load operation of the engine.

Generally, the low-speed fueling or idling system incorporated in the prior art carburetor includes an idle port and by-pass ports in communication with the float chamber via a pilot jet, those ports being opened in the throttle bore or induction pipe adjacent the throttle valve. When the throttle valve is closed or slightly opened for idling, starting or low-load running of the engine, the fuel with breeding air is discharged in the induction pipe through the idle port or by-pass ports. With such ordinary arrangement of idling system, however the difficulties have occurred in that the action of the breeding air only is not enough to effect full atomization or vaporization of the liquid fuel as desired, so that a large portion of the fuel adheres or drifts around the inner wall surface of the induction pipe, still in the state of liquid, and is forced into the associated combustion chambers in the engine. Because of this significant supply of not-atomized fuel into the combustion chambers, it was necessary to provide an additional or excessive supply of fuel so as to secure an adequate air-fuel ratio. This naturally caused vexious problems e.g. of increasing detrimental ingredients such as HC, CO, etc. contained in the exhaust gas, as well as instabilities of the engine operation in idling and excessive fuel consumption. Further, another problem has been raised in that since the liquid fuel travels along the inner wall surface of the carburetor's induction pipe and the intake manifold of the engine, the combustion chambers are supplied with the liquid fuel in pulsatory motion thereby causing instabilities of the engine revolution. Still another problem has been that in the case of a single carburetor for fuel distribution to a number of combustion chambers, the ratio of fuel distribution shows unevenness as one of the combustion chambers nearest the carburetor tends to be excessively supplied with the fuel, hence causing objectionable vibrations or unsteady running of the engine. Still further, there has been involved the difficulty that since the fuel takes rather a lengthy period of time to reach the associated combustion chambers, the working response of the engine is deteriorated.

SUMMARY OF THE INVENTION

This invention, therefore, is directed to eliminate the above prior art drawbacks by providing a carburetor for internal combustion engines of the type comprising an induction pipe horizontally arranged downstream of the Venturi portion, a butterfly-type throttle valve, and an idle port on the upper wall of the induction pipe being opened in the induction pipe adjacent the position assumed by the top peripheral edge of the throttle valve when the valve is closed or slightly opened, characterized by the provision of passage means formed around the inner surface of the induction pipe, said passage means functioning to prevent fuel discharged through the idle port from flowing along the upper inner

wall surface of the induction pipe in the downstream direction and conduct said flow of fuel downwardly and above the junctures between a valve shaft for supporting the throttle valve and the induction tube wall, and further passage means formed around the journal portions of the valve shaft, said further passage means functioning to conduct said fuel flow, which has reached above the valve shaft, to the lower central surface area of the throttle valve while turning the flow apart from the inner wall of the induction tube.

With the above described arrangement of the invention, therefore, it is assured that in idling operations of the engine, the flow of not-atomized fuel from the idle port or by-pass ports that otherwise could be carried in the state of liquid along the inner wall surface of the induction pipe toward the combustion chambers of the engine, is all captured by the passage means and caused to flow downwardly circumferentially along said passage means under the influence of its self-weight or suction force produced in the induction pipe, to be gathered around the central surface area of the throttle valve through said further passage means. The liquid fuel thus gathered on the valve further flows downwardly while spreading out over the surface area of the valve, so that all the volume of liquid fuel will be atomized by the action of a high-speed flow of suction gas passing through a minor clearance provided by the lower end of the throttle valve which has been closed.

Thus, the extra or additional effect of fuel atomization is advantageously provided at the lower end of the throttle valve in addition to the ordinary one by air breeding through the idle port or by-pass ports. Together with this twofold effect of fuel atomization the arrangement of the invention warrants that all the volume of fuel discharged from the ports as not-atomized or in the state of liquid be completely atomized through the lower valve gap before leaving the induction pipe of the carburetor, whereby avoiding the prior art problems of inadvantageously supplying some amount of liquid fuel into the associated engine cylinders. Hence, the invention is in effect advantageous in that because of no liquid fuel being taken in the engine cylinders it is possible to set the desired air-fuel ratio with a fuel mixture far leaner than that in the prior art carburetor which has needed an excessive supply of fuel, thereby detrimental substances such as HC, CO, etc. involved in the exhaust gas are significantly reduced in quantity. Further, the invention has advantages of reduction in fuel consumption, stabilities in the engine operation, and improvements on the response characteristic of the engine as well as its starting characteristic under cold conditions.

BRIEF DESCRIPTION OF THE DRAWINGS

FIG. 1 is a longitudinal sectional view of a carburetor incorporating a first embodiment of the invention;

FIG. 2 is a section taken along the line II — II of FIG. 1;

FIG. 3 is a section taken along the line III — III of FIG. 2;

FIG. 4 is an enlarged section showing the arrangement around the throttle valve according to the first embodiment of the invention;

FIG. 5 is an enlarged section of the same arrangement however according to a second embodiment the invention;

FIG. 6 is a perspective view of the valve and shaft assembly according to the second embodiment of the invention;

FIG. 7 is an enlarged section of the arrangement around the valve according to a third embodiment of the invention;

FIG. 8 is an enlarged section of the same arrangement however according to a fourth embodiment of the invention;

FIG. 9 is also an enlarged section of the same arrangement still however according to a fifth embodiment of the invention;

FIG. 10 is a perspective view of the valve and shaft assembly according to the fifth embodiment of the invention;

FIG. 11 is an enlarged section of the arrangement around the valve according to a sixth embodiment of the invention;

FIG. 12 is a section taken along the line XII — XII of FIG. 11;

FIG. 13 is a section taken along the line XIII — XIII of FIG. 11;

FIG. 14 is a section taken along the line XIV — XIV of FIG. 11; and

FIG. 15 is a perspective view of the valve and shaft assembly according to the sixth embodiment of the invention.

DESCRIPTION OF THE PRESENTLY PREFERRED EMBODIMENT

FIGS. 1, 2, 3 and 4 show a carburetor and its portion incorporating the first embodiment of the invention.

In FIG. 1, the carburetor 1 principally includes: a substantially horizontally extending air intake pipe 2; a piston valve 5 for varying the sectional area of the Venturi portion 4 in response to negative pressure produced in the induction pipe 3 by the manifold suction of the associated engine (not shown); a float chamber 6 for fuel storage with a constant fuel level; and a throttle valve 7 which is operatively connected to the accelerator pedal (not shown) for rotation to vary the valve opening in the induction pipe 3.

The piston valve 5 is slidably supported in a piston valve cylinder 8 which is integrally formed with the intake pipe 2. The piston valve 5 is provided at the top with a diaphragm 9 secured in air-tight manner, forming a suction chamber 10 with a casing 11. A coil spring 12 is anchored on the casing 11 so as to urge the piston valve 5 in the downward direction. The bottom of the piston valve 5 provides a surface portion 14 being tapered downwardly as viewed from the air intake side 13, a horizontal surface portion 15, an orifice 16 through which air in the suction chamber 10 is drawn out by negative pressure produced in the Venturi portion 4, and a jet needle 18 which is adapted to be thrusted deep in a coworking needle jet 17.

The float chamber 6 is formed by the lower wall of the air intake pipe 2 and a float chamber casing 19. The float chamber 6 stores in it a volume of fuel with a constant fuel level 22 attained by means of a needle valve 20 and a float 21. A supporting block 23 having a port 25 opened in the chamber is provided integral with the float chamber case 19, supporting a main jet 24 and the needle jet 17 in alignment with the piston valve 5. The needle jet 17 is opened in the Venturi portion 4 in the intake pipe 2. Further, the supporting block 23 supports a pilot jet 26 in a passage 37 branched from above

the main jet 24. The pilot jet 26 has an opening 27 which is in communication via a passage 29 with an air jet 28 opened around the outer periphery of the air intake 13.

The pilot jet 26 is further communicated with an idle port 31 and by-pass ports 33 through a passage 30 extending across the induction pipe 3. The idle port 31 is opened on the inner upper wall surface of the induction pipe 3, in the vertical direction, and more specifically it is located slightly downstream of the position of the upper edge of the throttle valve 7 that is to be assumed when the valve 7, which is secured on a valve shaft 33 by screws 34, is closed. The by-pass ports 32 are opened upstream of the idle port. Above the idle port, there is provided an adjustable screw 35 for control of air-fuel flow through the idle port 31.

Around the inner wall surface of the upper half section of the induction pipe 3, there is essentially provided a semicircumferentially extending passage means 36 in the form of a groove having a substantially U-shaped section opened in the induction pipe, which groove extending from adjacent one journal portion 33A, facing downstream, of the valve shaft 33 to adjacent the other journal portion 33A, facing downstream, of the shaft, in the assumed position of the valve being closed, after passing downstream the idle port 31. The journal portions 33A of the valve shaft 33 are of circular section, and the intermediate portion 33B of the shaft exposed in the induction pipe 3 is flattened by reducing the thickness by one-fifth to one-fourth of the diameter of the journal portion so as to constitute two parallel plane surfaces 39A, 39B symmetrical with each other in respect of the shaft axis. While the surface 39A facing upstream extends fully across the bore of the induction pipe 3, the surface 39B is bounded at each lateral end by further passage means in the form of an inclined step surface 40 which extends with an angle of 45° in respect to the shaft axis starting from slightly outside the respective lower end of the above described semicircumferential groove 36 while terminating at the inner location about one-sixth of the induction pipe diameter apart from the pipe wall. This step surface 40 is substantially vertical with respect to the surface 39B. Both of the two convergent passage means 40 thus constitute extensions of the above described semicircumferential groove 36. Between the two plane surfaces 39A, 39B, is formed a slot 41 into which the throttle valve 7 is inserted and secured by fastening screws 34. The throttle valve 7 is in operative association with the accelerator means (not shown) through the valve shaft 33. With the accelerator means set for idling, the throttle valve 7 is closed with minor gaps 42 provided on the upper and lower ends of the valve.

According to the carburetor 1 arranged above, the idling system will be operated as follows.

Due to the generation of suction or negative pressure in the induction pipe caused from the suction force by the engine cylinder, air flows in through the upper and lower valve clearances 42 while fuel from the pilot jet 26, which has been air-bred by the breeding passage 29, is drawn in the induction pipe 3 through the idle port 31 and by-pass ports 32. In this instance, a minor portion of the fuel is atomized and supplied to the engine as a mixture gas. However, a major portion of the fuel which has not been atomized is conducted by the air stream through the valve clearances 42 to spread out upon the inner wall surface of the induction pipe 3

from the idle port 31 and by-pass ports 32, and is drawn downstream in the liquid form adhering upon the inner wall surface of the pipe 3. When this liquid fuel reaches the passage means or semicircumferential groove 36, it is prevented from flowing further downstream, and is conducted downwardly along the groove 36. Two dependent flows of that fuel is then conducted by the respective passage means or inclined step surfaces 40 formed on the valve shaft 33 to change their flow directions so that they tend to converge around the center area of the downstream surface of the throttle valve 7. Subsequently, the flows of liquid fuel reach the bottom of the valve 7, where the fuel is subjected to a high-speed stream of air through the valve clearance 42 so that the fuel is completely atomized and drawn downstream in the pipe 3 toward the associated engine.

It is to be noted that since the inner or lower end of each passage means 40 is located with a distance L from the inner wall of the induction pipe 3, the fuel will never attach on the inner surface of the induction pipe 3 while falling along the surface of the throttle valve 7. Also, it is to be noted that although the convergent passage means 40 have been described as inclined by 45°, this inclination may alternatively be from 30° to 60°, depending on the application circumstances. However, the range from 35° to 65° has generally proved most desirable in terms of compatibly securing a smooth flow of fuel on the inclined step surface 40 and prevention of the fuel being drifted to the inner wall surface of the pipe 3.

FIGS. 5 and 6 show the second embodiment of the invention, wherein only the arrangement around the induction pipe is shown as other parts or portions are the same as described with reference to the first embodiment.

The semicircumferentially extending passage means 36A provided around the inner wall surface of the induction pipe 3 is in the form of a groove having a U-shaped section extending from above one journal portion of the valve shaft 33 to above the other journal portion of the shaft 33. However, this groove is shaped such that for the upper half length of the groove, the side wall 136A on the upstream side shows a gradual increase of angle relative to the inner surface of the induction pipe 3, as shown, from the top toward the middle of the groove length, in a manner that the side wall 136A forms a curved surface having gradually changing slopes relative to the bottom, while the side wall 136B on the downstream side and the side wall 136A extending over the lower half length of the groove are substantially perpendicular to the inner surface of the pipe 3. The valve shaft in this embodiment is uniformly of circular section, securing the throttle valve 7 inserted into a slot formed longitudinally, centrally of the shaft by means of fastening screws 34. The valve shaft 33 is provided at each journal portion with passage means 64 in the form of an inclined through-hole starting from the juncture between the downstream surface of the throttle valve and the upper portion of the shaft journal, toward the lower center of the valve, through the shaft. In the valve closed position, the upper opening 65 of each through-hole 64 is adapted to be located for substantially continuous communication with the respective lower end of the passage means 36A, and each through-hole 64 extends over both axial sides of the junction 66 between the valve shaft and the inner surface of the induction pipe 3. The inclination of each

passage 64 is set at around 45° in angle with respect to the shaft axis.

With this arrangement of the second embodiment, almost the same effect can be obtained in conducting the flow of liquid fluid along the two passage means, for full atomization through the bottom clearance 42, as that described with reference to the first embodiment. Additionally, however, it will be assured that thanks to such gradual changes in the sectional shape of the groove, there occurs a flow of air directed downward in and along the passage 36A so that the downward movement of the liquid fuel therealong be far more facilitated. This will results in the provision of a better response character of the associated engine.

15 In the third embodiment of FIG. 7, there is provided passage means in the form of substantially semi-cylindrical conducting member 36B which is fittingly inserted in the induction pipe 3 and secured by a bolt 136C. The conducting member 36B has its upstream edge which extends semicircumferentially between both journal portion areas of the valve shaft and forms a surface 136D substantially perpendicular to the inner surface of the induction pipe 3. Also, there is provided further passage means on the valve and shaft assembly 20 in the form of a valve supporting member 50 having a trapezoid section. Its bevel side surfaces form minor angles with the downstream surface of the valve 7. With this arrangement, the flow of liquid fuel is guided 25 downwardly along and by the surface 136D of the passage means 36B also with the additional aid of an air flow occurring therealong in the downward direction, and then the liquid fuel is further conducted toward the bottom of the valve though the surface 40 and the bevel side surface 50A of the supporting member 50. Thus, 30 a very smooth and rapid flow of liquid fuel is secured in the overall length of conducting passage.

35 FIG. 8 shows the fourth embodiment of the invention, which is the same as the third embodiment excepting the sectional configuration of the upstream edge of the passage means. As shown, the semi-cylindrical passage means 36C has the upstream edge of trough-like section opened to the upstream with the inner extreme end 136F projecting a little more upstream than the outer extreme end 136E. This arrangement secures reliable conduction of the fuel flow in a desired and positive manner as well as a quick flow of the liquid fuel by the aid of an air stream easily occurring along the passage means.

40 FIGS. 9 and 10 show the fifth embodiment which is the same as the previous embodiments of FIGS. 1 through 4 excepting passage means provided on the throttle valve, valve shaft and inner wall of the induction pipe. As shown, passage means 36D consists of a groove 51 according to the first embodiment and a semi-cylindrical member 52 similar to the member 36B of the third embodiment. In FIG. 10, the valve shaft 53 having journal portions 53A of circular section provides the intermediate portions 53B adapted to be exposed in the induction pipe 3. This intermediate portion 53B is reduced in thickness from the downstream side so as to be of crescent shape in section, and the throttle valve 7A is secured on the surface 53B by screws 34. Around the juncture between the valve 7A and the inner end of each journal portion 53A, the valve shaft provides a cut-out portion 54 of plane surface perpendicular to the surface of the valve 7A and inclined by 45° with respect to the axis of the shaft 53.

It is of course arranged that in idling or when the valve 7A is slightly opened, each cut-out portion 54 is positioned in continuation with the respective lower end of the above described passage means 36D. Also, the valve 7A is provided with a couple of passage means 55 each in the form of a substantially triangular plate member which has a thickness corresponding to that of the valve and a main side surface 56 being inclined 45° with respect to the shaft axis. The upper end of the surface 56 is formed in continuation with the respective cut-out portion 54. The lower end 57 of the surface 56, or plate member 55 terminates with a distance of about one-fourth of the vertical center height of the valve apart from the bottom of the valve. In like manner, with this arrangement, there can advantageously be secured a quick flow of air directed downward along the groove 51 due to differential air pressure between the top and bottom groove zones, thereby downward conducting of the liquid fuel therealong being facilitated. The cut-out portions 54 and the surfaces 56 of the plate member 55 serve to guide the flow of liquid fuel to be delivered onto the surface of the valve 7A in a widely dispersed pattern, as best shown in FIG. 10. Thus, the liquid fuel undergoes a significantly wide range of atomization at the valve gap 42.

FIGS. 11, 12, 13, 14 and 15 show the sixth embodiment of the invention.

Here, passage means 36E is constituted with a groove 58 formed around the inner wall surface of the induction pipe 3 and a further groove 59 formed at the upstream edge of a semi-cylindrical member 136G so that substantially tubular passage means be provided. As best shown in FIGS. 12 through 14, the grooves 58 and 59 show the same radius in section if taken along the same section, but these radii are reduced gradually toward the lower end of the tubular passage so that atop the passage, the tubular inner space 36E be maximum opened, in the upstream direction, with the projection edge 60 of the member 136G spaced most apart from the groove 58, while the inner space 36E is closed with the projection 60 being in contact with the inner wall surface of the induction pipe 3, at the level one-fourth of the passage length apart from the bottom. As seen in FIG. 15, the valve shaft 61 with journal portions 61A and the intermediate portion 61B similar to the fifth embodiment, is provided with step surfaces 62, 62 each with 45° inclination, perpendicular to the upstream surface of the valve 7 similarly secured on the intermediate portion 61B by screws 34. The upper end of each step surface 62 is located within the journal portion 61A, extending beyond the lower end of the respective passage means 36E.

This arrangement achieves the same effect as with the fifth embodiment however with a more effective advantage of using the action of air stream through the lower half length of closed passage. Similarly to the previous embodiments, there can advantageously be provided a very quick flow of liquid fuel all the way along the passage 36E and surfaces 62 formed on the valve shaft 61 and wide dispersion of the liquid fuel upon the surface of the valve so as to be fully atomized at the lower gap. No drifting of the liquid fuel off the valve surface or onto the inner surface of the induction pipe will occur.

I claim:

1. A carburetor for internal combustion engines of the type comprising an induction pipe horizontally ar-

ranged downstream of the Venturi portion, a butterfly-type throttle valve journal supported by said induction pipe, and an idle port on the upper wall of the induction pipe being opened in the induction pipe adjacent the position of the top peripheral edge of the throttle valve to be assumed when the valve is closed or slightly opened, characterized by the provision of passage means formed around the inner wall surface of the induction pipe, said passage means functioning to prevent fuel discharged through the idle port from flowing along the upper inner wall surface of the induction pipe in the downstream direction and conduct said flow of fuel downwardly to and above the junctures between a valve shaft for supporting said throttle valve and the induction pipe wall, and further passage means formed around the journal portions of the valve shaft, said further passage means functioning to conduct said fuel flow, which has reached above the valve shaft, to the lower central surface area of the throttle valve, while turning the flow apart from the inner wall of the induction pipe.

2. A carburetor for internal combustion engines according to claim 1, characterized by that when the throttle valve assumes the closed or slightly opened position, said passage means provided around the inner wall surface of the induction pipe is such arranged as extending from above one journal portion of the valve shaft and behind the downstream surface of the throttle valve, to above the other journal portion of the valve shaft, passing closely downstream of said idle port; while said further passage means on the valve shaft extending slightly downstream of said surface of the throttle valve, as inclined with respect to the shaft axis from each upper end portion of the valve shaft located outwardly of the inner wall surface of the induction pipe, toward the lower inner central portion of the induction pipe.

3. A carburetor for internal combustion engines according to claim 2, characterized by that said passage means provided around the inner wall surface of the induction pipe consists of a groove formed on the inner wall surface of the induction pipe.

4. A carburetor for internal combustion engines according to claim 3, characterized by that said groove is of substantially U-shaped section opened inwardly of the induction pipe.

5. A carburetor for internal combustion engines according to claim 4, characterized by that said groove of U-shaped section is such shaped over the length thereof that one side wall surface of said groove on the upstream side has a gradual increase of gradient formed from the inner surface of the induction pipe to the bottom surface of the groove while the varying rate of said gradient being increased toward the lower portion of the induction pipe.

6. A carburetor for internal combustion engines according to claim 2, characterized by that said passage means provided on the inner wall surface of the induction pipe consists of a member secured on the inner wall surface of the induction pipe.

7. A carburetor for internal combustion engines according to claim 6, characterized by that said member secured on the inner wall surface of the induction pipe is in the form of a semi-cylindrical member which has the outer circumferential surface substantially identical to the inner circumferential surface of the induction pipe, and the end surface of said member on the up-

stream side is substantially perpendicular to the inner wall surface of the induction pipe.

8. A carburetor for internal combustion engines according to claim 6, characterized by that said member secured on the inner wall surface of the induction pipe has the outer circumferential surface substantially identical to the inner circumferential surface of the induction pipe, the end surface of said member on the upstream side forming, in cooperation with the inner wall surface of the induction pipe, a groove of U-shaped section opened upstream.

9. A carburetor for internal combustion engines according to claim 2, characterized by that said passage means provided around the inner wall surface of the induction pipe consists of a groove formed on the inner wall surface of the induction pipe and a semi-cylindrical member secured on the inner wall surface of the induction pipe in such a manner that over the length of the groove, at least a half width of the opening, on the upstream side, of the groove opened inwardly is in direct communication with the interior of the induction pipe, the outer circumferential surface of said member being substantially identical to the inner circumferential surface of the induction pipe.

10. A carburetor for internal combustion engines according to claim 9, characterized by that said groove is of substantially U-shaped section while said semi-cylindrical member being arranged such that the end surface of said member on the upstream side being substantially perpendicular to the inner wall surface of the induction pipe, and over the length of the groove, a half width of the opening on the downstream side being closed by said member.

11. A carburetor for internal combustion engines according to claim 9, characterized by that said groove provided around the inner wall surface of the induction pipe and a groove formed on the outer side of the upstream end portion of said semi-cylindrical member in combination forms a passage generally closed such that over the upper half length, said passage is opened in the upstream direction with a gradual increase of the opening toward the top of the passage.

12. A carburetor for internal combustion engines according to claim 2, characterized by that said further passage means on the valve shaft each extends from a portion of the inner wall surface of the induction pipe, where the outer circumferential edge of said valve shaft intersects the induction pipe, to the downstream surface of said throttle valve spaced inwardly from said inner wall surface of the induction pipe.

13. A carburetor for internal combustion engines according to claim 12, characterized by that said further passage means on the valve shaft each is substantially perpendicular to the downstream surface of said throttle valve while said passage means each consists of a plane surface which is adapted to turn upward when said throttle valve closes.

14. A carburetor for internal combustion engines according to claim 13, characterized by that said throttle valve is supported by the valve shaft as being inserted through an axial opening provided on a portion of said valve shaft extending within the induction pipe, said axial opening having the width corresponding to the thickness of said throttle valve and the length corresponding to the minor diameter of said valve, said portion of the valve shaft, at the downstream side of the valve, having a cross section of trapezoid with a plane

surface parallel to the downstream surface of the throttle valve, while the inner end surface of each journal portion projecting inwardly of the induction pipe so as to form passage means on the valve shaft.

15. A carburetor for internal combustion engines according to claim 13, characterized by that said portion of the valve shaft exposed within the induction pipe has a semicircular section with the chord extending at the downstream side, said throttle valve being secured on said chord containing surface of the valve shaft, while the inner end surface of each journal portion projecting inwardly of the induction pipe so as to form the passage means on the valve shaft.

16. A carburetor for internal combustion engines according to claim 12, characterized by that said passage means consists of passages of circular section formed through the valve shaft so that the outer extreme end of the upper opening of each passage formed on the valve shaft is positioned outwardly of the inner wall surface of the induction pipe and the inner extreme end of said upper opening of each passage is positioned inwardly of the inner wall surface of the induction pipe, while the outer extreme end of the lower opening of each passage is positioned inwardly of the inner wall surface of the induction pipe.

17. A carburetor for internal combustion engines according to claim 2, characterized by that said throttle valve is in continuous communication with said further passage means on the valve shaft, while said throttle valve being provided on the downstream surface thereof with passage means for conducting a flow of liquid fuel, which has been conducted onto the throttle valve by said passage means provided on the induction pipe and valve shaft, to the downstream surface of said throttle valve spaced inwardly from the inner wall surface of the induction pipe.

18. A carburetor for internal combustion engines according to claim 17, characterized by that said passage means provided on the downstream surface of the throttle valve consists of members each having a plane top surface which continuously extends from the inner end portion of said further passage means on the valve shaft in the diagonal downward direction toward the lower inner central portion of the induction pipe, the inner end of each member being positioned inwardly of the outer peripheral edge of the throttle valve.

19. A carburetor for internal combustion engines according to claim 14, characterized by that said passage means provided around the inner wall surface of the induction pipe consists of a groove having a substantially U-shaped section opened inwardly of the induction pipe.

20. A carburetor for internal combustion engines according to claim 16, characterized by that said passage means provided around the inner wall surface of the induction pipe consists of a groove of substantially U-shaped section opened inwardly of the pipe, said groove of U-shaped section being such shaped over the length thereof that one side wall surface of said groove on the upstream side has a gradual increase of gradient formed from the inner wall surface of the induction pipe to the bottom surface of the groove, while the varying rate of said gradient being increased toward the lower portion of the induction pipe.

21. A carburetor for internal combustion engines according to claim 18, characterized by that said passage means provided around the inner wall surface of the in-

duction pipe has a substantially U-shaped section opened inwardly of the induction pipe, while there being provided a semi-cylindrical member having the outer circumferential surface substantially identical to the inner circumferential surface of the induction pipe, the end surface of said member on the upstream side being substantially perpendicular to the inner wall surface of the induction pipe, said member being positioned so as to substantially close a half width of the groove opening, on the downstream side, over the length of the groove.

22. A carburetor for internal combustion engines ac-

cording to claim 15, characterized by that said passage means provided around the inner wall surface of the induction pipe consists of a groove formed on the inner wall surface of the induction pipe and a further groove formed on the outer side of the upstream end portion of a semi-cylindrical member secured on the inner wall surface of the induction pipe, thereby forming a generally closed passage such that over the upper half length, said passage is opened in the upstream direction with a gradual increase of the opening toward the top of the passage.
